UNITED STATES PATENT OFFICE.

HARLEY S. HEATH, OF HARROD, OHIO.

DISTRIBUTER AND PACKER FOR SILOS.

1,358,732.

Specification of Letters Patent. Patented Nov. 16, 1920.

Application filed June 11, 1919. Serial No. 303,316.

To all whom it may concern:

Be it known that I, HARLEY S. HEATH, a citizen of the United States, residing at Harrod, in the county of Allen, State of Ohio, have invented certain new and useful Improvements in Distributers and Packers for Silos; and I do hereby declare the following to be a full, clear, and exact description of the invention, such as will enable others skilled in the art to which it appertains to make and use the same.

This invention relates to new and useful improvements in silo distributing and packing devices.

One object of the present invention is to provide a novel and improved device of this character whereby the silage is delivered into the silo and distributed evenly from the center toward the side, and firmly packed down.

Another object is to provide a novel and improved device of this character wherein there is a means for throwing the silage evenly before the packing roller, and which is arranged to travel in unison with the roller, about the center of the silo.

A further object resides in the provision of novel and improved means for supporting the parts and for driving the distributor and the packer.

Other objects and advantages will be apparent from the following description when taken in connection with the accompanying drawings.

35 In the drawings:

Figure 1 is a vertical sectional view through a silo showing the invention in side elevation.

Fig. 2 is a top plan view of the device and silo, the feed pipe being shown in section.

Fig. 3 is a sectional view taken vertically through the silo in a plane at right angles to that of Fig. 1, showing the edge view of the distributor wheel.

Fig. 4 is a vertical longitudinal sectional view taken centrally through the packer roller.

Fig. 5 is a vertical sectional detail view taken on the line 5—5 of Fig. 3, through the distributor wheel.

Fig. 6 is an outer end elevation of the packer roller showing the manner of connecting the sections together.

Referring particularly to the accompanying drawings, 10 represents the silo outside of which is disposed the vertical silage conveying pipe 11, and connected to the goose-neck, or arched upper end 12 of the said pipe, is the sectional pipe 13, which extends down into the silo for feeding the silage into the silo. Disposed within the silo, and extending from the center thereof to one side of the silo, is a horizontally arranged frusto-conical roller, represented as a whole by the numeral 14. This roller is formed of the longitudinally extending segments 15 each having an inwardly extending apertured lug 16 which is arranged in registration with the lug of the next adjacent segments for the reception of retaining bolts 17. Extending longitudinally through the center of the roller is a telescoping shaft 18, the outer end of which is supported in the adjacent end of a frame bar 19, while the inner end is supported in bearing eye 20, formed in one end of a horizontal and radial telescopic arm 21. Extending vertically from this arm 21, inwardly of the bearing eye 20, is an upright frame member 22, the upper portion of which supports a rectangular frame 23. Located within this frame and having the ends of its axle or shaft 24 journaled in the side members of said frame, is a paddle wheel 25 disposed in such position that it throws the silage in front of the packing roller 14. A smaller frame 26 is mounted on the side of the upright 22, and in this upright and the adjacent side of the smaller frame 26 is supported the horizontal shaft 27. On the inner end of the shaft 27 is mounted a pinion 28 which meshes with a pinion 29 on the adjacent end of the shaft or axle 24 of the paddle or distributing wheel 25. On the outer end of the shaft 27 there is formed a worm 30 which meshes with the worm wheel 31 carried by a telescoping shaft 32 which is supported at one end in the frame 26 and at its other end in the upper end of an arm 33 which is carried by the frame bar 19 and extends above the surface of

the large or outer end of the roller 14. Carried by this outer end of the shaft 32 is a bevel-faced wheel 34 which bears frictionally against the peripheral surface of the 5 larger end of the roller.

On the outer end of the arm 21 there is mounted a wheel 35 which has a broad tread and which rolls on the upper surface of the silage as the device turns within the silo.

- 10 Extending vertically from this arm 21, inwardly of the wheel 35, is a short shaft 36 carrying on its upper end a horizontal wheel 37 which bears against the inner face of the wall of the silo. Extending from the 15 outer end of the arm 21 to a point adjacent the outer or larger end of the packing roller 14, is a telescoping brace 38 which is hinged at this end to the frame bar 19. As seen in Fig. 3 only, the brace 38 may be additionally 20 supported by an inclined rod 39 which extends from the upper end of the frame 23. Carried by the brace is a vertical shaft 40 which has a horizontal wheel 41 on its upper end for engagement with the inner face of 25 the silo wall in the same manner as the wheel 37. These wheels 37 and 41 serve to keep the outer end of the roller 14 from frictionally engaging with the wall of the silo during the operation of the device, and as 30 the device rotates within the silo.

Disposed tangentially with respect to the paddle wheel and thereabove, is a discharge pipe 42, into the upper end of which is engaged the lowermost section of the pipe 13.

- 35 Extending longitudinally in the front of the packing roller 14, and supported, adjustably, at its ends on the members 21 and 19, is a plate 43 which evenly distributes the silage ahead of the roller, as the device turns 40 within the silo.

The silage is delivered through the pipe 11 and pipe 13, by an air blast and strikes the paddles of the wheel 25 with such force as to cause the rotation thereof. By reason 45 of the geared connections with the packing roller, which rests on the upper face of the silage, and serves as the traction wheel of the device, the entire structure within the silo will be revolved about the bearing point 50 20, as the silage is delivered to the wheel 25 and causes the rotation thereof. Thus the action of feeding the silage, distributing the same evenly, and packing it down, are accomplished by the force of the inflow of 55 the silage.

When it becomes necessary to use the device with a silo of such diameter that the outer or larger end of the packing roller will not reach to the side wall of the silo, provision is made for increasing the length 60 of the roller by adding sections thereto, at the larger end. In this case the members 18, 21, 32 and 38 are extended by reason of their telescopic nature. The vertical arm 33 is 65 provided with a longitudinal slot or bear-

ing 33' in which the adjacent end of the shaft 32 is adapted to be engaged, whereby the friction wheel 34 is rendered capable of properly engaging with the larger surface of the packing roller, when the same 70 has been extended for use in a silo of greater diameter.

By reason of the fact that the packing roller is hollow, silage can be packed therein to produce the required weight to the roller 75 for more efficient operation on the surface of the silage. A strong spring 19' is carried by the member 19 and bears on the adjacent end of the shaft 32 to hold the wheel 34 in firm contact with the packing 80 roller, so that said packing roller will be properly turned to move the mechanism about its center within the silo.

What is claimed is:

1. An automatic distributor and packer 85 for a silo comprising a rotatable frame, a packing element mounted on the frame, means for feeding the silage into the silo, and means carried by the frame and operatively connected to the packing element for 90 driving the latter and operated by the inflowing silage.

2. An automatic distributor and packer for a silo comprising a rotatable frame, a 95 packing roller carried by and movable with the frame, a motor driven by the inflow of silage, and operative connections between the motor and the packing roller.

3. An automatic distributor and packer for a silo comprising a rotatable frame, a 100 packing roller carried by and movable with the frame, a motor operatively connected with the roller for driving the same to turn the frame within the silo, and means for delivering silage to the motor for operating 105 the motor.

4. An automatic distributor and packer for a silo comprising a rotatable frame, a packing roller rotatably supported on the frame and revoluble with the frame, a silage 110 operated motor carried by the frame and operatively connected with the roller for driving the latter, and guiding means carried by the frame.

5. An automatic distributor and packer for a silo comprising a rotatable frame, a tapering packing roller rotatably mounted on the frame and movable therewith, a silage 115 driven motor carried by the frame, a shaft supported by the frame and extending longitudinally over the roller, driving connections between the shaft and the motor, and a friction wheel on the shaft engaging with the packing roller to rotate the same and simultaneously rotate the frame.

6. An automatic distributor and packer for a silo comprising a rotatable frame, radially extending and telescoping shafts and 120 arms carried by the frame, a sectional tapering packing roller mounted on one of said 130

shafts, wheels mounted on the outer ends of said arms, a feed pipe supported on the frame and movable therewith for feeding silage into the silo, a distributing plate for 5 the silage supported on the frame in advance of the packing roller, a rotatable wheel mounted on the frame, geared connections between the wheel and one of the shafts, operative connections between said shaft and 10 the packing roller, said feed pipe being

located in position to discharge silage to the rotatable wheel for driving the same and rotating the frame and the packing roller.

In testimony whereof I affix my signature in the presence of two witnesses.

HARLEY S. HEATH.
